UNITED STATES PATENT OFFICE

2,248,846

VACUUM ELECTRIC SWITCH AND PLATE

John A. Brewer, Kalamazoo, Mich.

Application May 9, 1940, Serial No. 334,263

4 Claims. (Cl. 200—33)

This invention relates to a vacuum controlled switch which will enable automatic opening at a predetermined time following the closing thereof.

It is aimed generally to provide such a construction which is improved and simplified and rendered exceedingly inexpensive, and a construction which is well adapted for embodiment in a wall plate or switch plate, so that the structure as a whole may be substituted for an ordinary wall or switch plate and rendered operative by the connection of the necessary two wires for the electric circuit.

The more specific objects and advantages will become apparent from a consideration of the description following taken in connection with accompanying drawings illustrating an operative embodiment.

In said drawings:

Figure 1 is a front elevation of a plate and switch embodying my invention;

Figure 2 is a rear view of the parts of Figure 1;

Figure 3 is a side edge elevation of the parts of Figures 1 and 2;

Figure 4 is a cross sectional view taken on the plane of line 4—4 of Figure 1 with the parts in open position;

Figure 5 is a section substantially similar to that of Figure 4 with the parts in switch closing position;

Figure 6 is a fragmentary elevation with the rear cover plate removed;

Figure 7 is a section taken on the plane of line 7—7 of Figure 1;

Figure 8 is a view similar to Figure 7 showing an intermediate stage of operation to close the switch;

Figure 9 is a section similar to Figure 7 showing the switch in closed position;

Figure 10 is a fragmentary elevation of a modified form of construction, and

Figure 11 is a cross section taken on the line 11—11 of Figure 10.

In carrying out the invention, a mounting or plate is provided at 10 preferably of a size similar to a wall plate or switch plate such as is used in connection with a wall switch, so that the same may be substituted for the cover plate of the wall switch and the switch parts within the same and be fastened in place by the same screws or fastenings as at openings 11. Such plate 10 may be of any desired material and of one piece or composite as shown in that it has a facing 12.

The plate 10 is interiorly recessed as at 13 and

therein a stationary contact 14 is mounted in coacting relation to a movable contact 15 and which contacts have terminals to which the conductor wires 16 of the circuit in which the device is connected, are attached.

Said contact 15 has a disc or plate 17 and an extension 18, which are normally spaced from the contact 14 and so urged by the inherent resilience of the contact. Both contacts 14 and 15 are preferably metallic. Disc or plate 17 is connected with the remainder of the contact 15 by a U-shaped neck at 19.

A vacuum cup 20, usually of elastic rubber is provided and movable in the recess 13 so that its free marginal edge 21 will engage the disc 17 and due to the vacuum within the cup, draw such disc 17 and extension 18 toward the contact 14, in order to close the electric circuit to the light or other device. The degree of vacuum engagement between the cup 20 and the disc 17 is minutely determined, so that the closing of the switch for the period intended, will be predetermined, for instance three or four minutes, even less or much more, the control being determined by leakage through a narrow slit 17a cut in disc 17, diametrically thereof, with a thin knife or razor blade.

In order to control the transverse movement of the vacuum cup toward and away from the disc 17, a leaf or strip spring 22 is provided across recess 13, its ends being anchored as at 23 in the plate. Intermediate its ends, said strip 22 has a convex portion 24 conforming to the convexity of the vacuum cup 20 and fastened to the latter by a rivet, bolt or the like 25. Said spring 22 is deformable at the portion 24 so as to be substantially straight as in Figure 8 and this result is accomplished by slidably mounting a depressor button 26 with a reduced shank 27, in an elongated slot 28 in the facing 12, such depressor button having an enlarged head exteriorly of the plate and being held in place by a pin or the like 29 passing through the shank on the opposite side of the facing 12. Such button 26 is normally at one end of the portion 24 or the other as in Figures 7 and 9 and it will be understood that the button 26 is manually engageable to slide it from one extremity of slot 28 to the other, thereby depressing the strip portion 24 as in Figure 8 and causing the vacuum cup to engage the disc 17 and through the continuous movement of the button 26, enable the resilience of portion 24 to restore the vacuum cup to its normal position moving with it the disc 17 and contact portion 18 into circuit closing relation with the

contact 14, which it maintains for the predetermined period of time, when the vacuum is automatically broken and the switch opened. For the succeeding operation of the switch, it will be understood that the movement of the button 26 will be in the opposite direction.

A closure plate 30 is provided at the rear of the recess 13, being held in place by screws or other fastenings 31.

In Figures 10 and 11, one of the many modified forms which may be resorted to within the spirit and scope of the invention, is shown. This form differs from the preceding form only in the means whereby the suction cup is mounted and controlled. The suction cup in this instance is designated 20' and co-acts with the contact 15 at disc portion 17 in exactly the same manner as in the first form. This form has a push button 32 integral with the cup 20', slidably mounted in and extending outwardly beyond a wall 33 of an extension 34 of the facing of the plate or the like. An arcuate metallic wire spring 35 or the equivalent passes through the push button 32 and has its terminals anchored in the extension 34. The resilience of spring 35 is such as to normally maintain the vacuum cup 20' retracted as shown in Figure 11 with the contacts in open position. However, in order to close the switch, the button 32 is pressed inwardly to contact the disc 17 and then released so that the spring 35 will restore the vacuum cup to its normal position, the latter moving with it the contact disc 17 and closing the switch, which automatically opens at the predetermined time, through the leakage of air through air channel 35 provided by slit 17a in disc or plate 17 into the same.

I claim as my invention:

1. A device of the class described having a pair of contacts, a vacuum cup movable bodily into engagement with one of the contacts to move it to closed position to maintain it in closed relation to the other, and deformable spring means mounting the vacuum cup for movement bodily into engagement with the co-acting contact.

10 2. A device of the class described having a pair of contacts, a vacuum cup engageable with one of the contacts to maintain it in closed relation to the other, deformable spring means mounting the vacuum cup for engagement with the co-acting contact, said spring means having an arcuate portion normally maintaining the vacuum cup retracted and returnable to normal shape through its resilience.

20 3. A device of the class described having contacts, a vacuum cup engageable with one of the contacts to maintain it in closing relation to the other for a predetermined period of time, a spring mounting said vacuum cup, said spring having a depressible portion, and a slide movable over said depressible portion to move the vacuum cup into engagement with the co-acting contact.

25 4. A device of the class described having contacts, a vacuum cup engageable with one of the contacts to maintain it in closing relation to the other for a predetermined period of time, a spring mounting said vacuum cup, said spring having a depressible portion, a slide movable over said depressible portion to move the vacuum cup into engagement with the co-acting contact, and a part having an elongated slot slidably mounting said button.

JOHN A. BREWER.
